EXPANDABLE GARMENT HANGER

Hartsel W. Pace, 5815 Garford St., Long Beach 15, Calif.

Filed July 29, 1958, Ser. No. 751,768

1 Claim. (Cl. 223—95)

This invention relates to garment hangers and more specifically to an expandable hanger for women's skirts and other clothing.

One object of the invention is to provide a garment holder which is of light weight construction and so designed that the same may be readily grasped and manipulated to provide a controlled length for garment holding purposes.

Another object of the invention is to provide a garment holder of the type set forth having a support bar composed of two sections of molded composition materials wherein one section has a key and the other section a mating keyway for strengthening the support bar.

A further object of the invention is to provide a simple garment holder length adjustment through clips which may be readily moved and which stay in the desired position when once set and which maintain the two sections of the support bar in close contact whereby the key and keyway contribute the maximum strengthening to the assembly.

A further object of the invention is to provide a hanger which may be readily collapsed and hence will occupy less storage space during shipping and storage than previously known types of hangers.

Other objects and many of the attendant advantages of this invention will be readily appreciated as the same becomes better understood by reference to the following description.

Fig. 1 is a perspective view of a garment hanger embodying the invention;

Fig. 2 is a detail view of portions of the support bar showing the strengthening key and keyway;

Fig. 3 is a perspective view of one of the two clips used on the garment holder shown in Fig. 1; and

Fig. 4 is a view in section taken along the line 4—4 of Fig. 3 and showing more clearly the rounded detent button on the inner wall of the clip.

As shown in Fig. 1, the garment holder comprises a support bar 8 made up of a first section or member 10 and a second section or member 12. The two sections are generally similar and differ only in that section 12 is provided with a keyway 14 which key 16 of section 10, as shown in Fig. 2, engages with a sliding fit.

A series of depressions 18 are provided in the wide outer faces of sections 10 and 12. Projections 20 and 22 on section 10 and projections 24 and 26 on section 12 serve to retain clips 28 and 30 respectively in position and effectively secure one clip to each section. The edges of the inner sides of sections 10 and 12 are broken to define V-grooves 32 and 33 when the support bar is assembled. Sleeves 34, made of rubber-like material and snugly fitting on the ends of the two sections, serve the purpose of gripping garment 36. Notches 38 are provided for holding garments which may be provided with straps. The garment holding assembly is supported by hanger rods 40 and 42 which engage clips 28 and 30 respectively and which are joined at the other end

2

to hook 44 by means of pivot pin 46 or other conventional means.

Fig. 2 shows the relationship of keyway 14 and key 16 and also the appearance of projections 24 and 26.

5 The clip shown in Fig. 3 comprises a four sided structure having a boss 48 on top which is provided with opening 50 into which a hanger rod may be inserted and retained. Wedge shaped guides 51 and 52 fit into grooves 32 and 33 of the support bar to aid in keeping 10 the clip in position. The detent button 54 fits into the depressions in the side of members 10 and 12. The action of detent button 54 in grooves 18 is to retain the required span between extremities of support bar 8 to suit different sizes of garments. The shape of button 54 is shown more clearly in Fig. 4. The clips are preferably formed of molded composition material.

In operation, the garment to be held is placed over sleeves 34 and the support bar is extended by pulling on members 10 and 12 until the desired length of the 20 support bar is attained and the detent buttons of the clips slide into place in the appropriate depression in the sides of sections 10 and 12. This detent action maintains a spaced relationship between opposing ends of arms 10 and 12. When it is desired to release the garment, 25 the length of the support bar is shortened by pushing on sections 10 and 12 thus freeing the garment. The short leg of clips 28 and 30 which contain the detent buttons is springy, by virtue of its construction, and is able to ride up over the material between depressions 18 when 30 hand pressure is brought to bear on the ends of the support bars. When packed for shipping, the hanger rods are detached from grooves 50 in clips 28 and 30 and the whole is then packed in a narrow rectangular display box which occupies very little space.

35 The configuration described permits the hanger to be light in weight and still very strong. The pull of a heavy garment must shear the key before the support bar will fail. Since the composition materials such as 40 polystyrene plastic, which is a preferred substance for making the sections, is extremely resistant to shearing stress, the hanger will be very sturdy. The manner in which the clips are fitted to the sections assists in preventing distortion through twisting. In particular, the fit of guides 51 and 52 in the mated openings at the top 45 and bottom of support bar 8 aids in maintaining proper alignment of the moving parts. Hard rubber, metal, wood, plastics, or combinations of these materials may be used in construction.

Obviously many modifications and variations of the 50 present invention are possible in the light of the above teachings. It is therefore to be understood that within the scope of the appended claim the invention may be practiced otherwise than as specifically described.

What is claimed is:

55 A garment holder comprising a hook, two support rods pivotally joined to said hook at one end, two four sided clips pivotally joined to the other ends of said support rods, each clip comprising upper and lower sides, a third side joining said upper and lower sides, and a springy 60 fourth side joined only to said upper side and having one end free, wedge shaped guides secured to the inner opposing upper and lower sides of each of said clips, a detent button secured to the inner fourth side of each of said clips, a support bar adjustably held by said two 65 clips and comprising a first section defining a plurality of detent depressions along the length thereof adapted to slidably engage the detent button of one of said clips and defining projections at one end adapted to maintain the other of said clips in fixed relation to said first section, a key running along the length of said first section and secured thereto, a second section generally similar

to said first section and defining a keyway adapted to slidably engage the key of said first section, said support bar defining two V-shaped grooves at the juncture of the upper and lower edges of the two sections and engaging the wedge shaped guides of said clips, and garment hanging means secured to said first and second sections at the end opposite that bearing the projections for maintaining said clips in position.
